CENTRIFUGAL CASTING APPARATUS

Robert E. Daniel, Birmingham, Ala., assignor to
United States Pipe and Foundry Company, a
corporation of New Jersey

Application April 9, 1942, Serial No. 438,258

8 Claims. (Cl. 22—65)

The invention relates to centrifugal casting apparatus and is directed specifically to means for clamping the driving sleeve to the bell end of a centrifugal mold used for making pipe or the like, and for providing a water seal between the driving sleeve and the mold.

In order that pipe of different diameter may be cast in such apparatus, it is customary to employ molds of varying diameter and to construct the different molds and the other parts of the casting apparatus so that a mold of one size may be easily replaced in the apparatus by a mold of another size. In thus changing from one mold to another, economy of operation requires that a minimum number of changes in other parts of the apparatus be made. It has usually been found expedient to provide the bell end of such a mold with an annular flange as a part of the construction utilized for supporting and rotating the mold in the apparatus and for providing a water seal.

In one arrangement commonly utilized the bell end of the mold is provided with a short extension which projects longitudinally beyond the flange, and this extension is externally threaded for cooperation with an internally threaded flange ring which forms a driving connection between the driving sleeve and the mold. Suitable packing or sealing gaskets have been necessary in order to form a water seal between the outer end of the driving sleeve and the outer end of the mold. The excessive heat to which the mold is subjected during the casting operation, the consequent expansion and contraction of the bell of the mold, and the excessive force required to tighten the flange ring on the threaded bell and remove it therefrom soon result in such damage to the cooperating threads on the mold and the flange ring that it becomes difficult, and frequently impossible, to secure water-tight connections at the bell end of the mold. This leads to undue expense in renewing the threads on the mold or renewing the entire bell portion.

In accordance with one arrangement which has heretofore been suggested for overcoming the above difficulties, the threads were omitted from the extension on the bell end of the mold and a metal driving ring was interposed between the driving sleeve and the mold flange. In the suggested construction, the driving ring was not designed to form a water seal between the driving sleeve and the mold, and the entire structure was such that it was impossible to provide a satisfactory water seal between the driving sleeve and the end of the mold.

In accordance with another arrangement which has been suggested heretofore, the driving sleeve was provided with an internal flange formed integral with the sleeve, and the flange on the bell end of the mold was clamped between this internal flange and the flange ring. With a construction of that character, the driving sleeve was adapted for use with only one size of mold so that when a mold of one size was replaced by a mold of another size in the casting apparatus it was necessary to substitute a different driving sleeve and a different flange ring. Such a construction necessarily required that many sizes of driving sleeves and flange rings be provided and maintained in order to adapt the apparatus to casting pipe of the various commercial sizes. The construction was also unsatisfactory in that it prevented the free circulation of water about the bell end of the mold with the result that the end of the mold was overheated during the casting operation.

One of the principal objects of the present invention is the elimination of the threaded connection between the bell end of the mold and the flange ring employed therewith. Another object is the elimination of packing and sealing gaskets between the driving sleeve and the mold. Another object of the invention is a reduction in the number of parts required for providing a satisfactory driving connection and water seal between the driving sleeve and the mold. A further object of the invention is the provision of a driving ring between the driving sleeve and the mold, which also serves as a water seal. A still further object is the provision of an interchangeable driving ring between the driving sleeve and the mold, which dispenses with the necessity for substituting another driving sleeve when a mold of one size is replaced by a mold of another size. It is another object of the invention to provide a driving ring which is so constructed that its position in the apparatus may be reversed to adapt it to mold flanges of different thickness. Still another object of the invention is the provision of driving and sealing means of such a construction as to effect a substantial saving in time and labor in the operation of changing from one size of mold to another and in correcting water leakage at the bell end of the mold. Still further objects and advantages of the improvement will be apparent from the following description, taken with the accompanying drawing wherein:

Fig. 1 is a side elevational view of one form
55 of centrifugal casting apparatus with the present

improvement incorporated therein, parts of the apparatus being shown in section to better illustrate the construction;

Fig. 2 is an enlarged sectional view through the bell end of the mold and connected parts as shown in Fig. 1, the improved driving and sealing ring being shown in the position in which it is adapted to be used with a mold flange of one thickness;

Fig. 3 is a view similar to Fig. 2, but showing the driving and sealing ring reversed in position to adapt it to a mold flange of less thickness;

Fig. 4 is a side elevational view of the improved driving and sealing ring, a part thereof being cut away to better illustrate its formation;

Fig. 5 is a side elevational view of the improved flange ring, a part thereof being cut away to better illustrate its formation; and

Fig. 6 is an end elevational view, partly broken away, of the flange ring shown in Fig. 5.

While the improvements disclosed and claimed herein may be utilized with other forms of apparatus, they are illustrated in connection with centrifugal casting apparatus such as that shown and described in Russell and Langenberg Patent 1,949,433, granted March 6, 1934, for Method and apparatus for casting pipes centrifugally. As shown in the drawing herein, such apparatus comprises a mold 10 removably and rotatably mounted in a water box 11 which serves as a movable carriage for the mold. The water box 11 is supported on wheels 12 which are arranged to travel upon side rails 13 on the base 14. A piston 15 operating in a cylinder 16 secured to the base 14 has its outer end connected to the under side of the mold carriage 11 by a coupling member 17 for moving the carriage to and fro on the rails 13 during the casting operation.

A pouring trough 18 of well known type is fixed at its inlet end to a suitable support rigid with respect to the base 14 so that the free or outlet end 19 may move into and out of the mold 10 as the mold carriage 11 is moved back and forth on the rails 13. The particular casting apparatus described above is well known in the industry, and it will be understood that when molten metal is supplied to the pouring trough 18 during the operation of the apparatus a stream of metal is deposited in the mold 10 in the form of a spiral extending from end to end of the mold, and that the action of centrifugal force generated by the rotation of the mold and acting upon the poured metal distributes the metal uniformly over the inner surface of the mold.

Rotary movement of the mold 10 is provided by an electric motor 20 mounted on the water box 11 and movable therewith. Motion is transmitted from the motor 20 to the mold 10 through gears 21 and 22, the teeth of the latter meshing with teeth 23 on the outside of a driving sleeve 24 of a form which is generally well known in apparatus of this character. The driving sleeve 24 surrounds the bell of the mold 10 and its outer end is designed to be suitably connected with the outer end of the bell while its inner end is mounted for rotational movement in a bearing member 25 fixed in the water box 11. A water seal may be provided between the driving sleeve 24 and the bearing member 25 by suitable packing rings 26 fitting within annular grooves 27 in the outer surface of the driving sleeve.

As disclosed in Figs. 1, 2 and 3 of the drawing, the driving sleeve 24 is spaced throughout its length from the outer surface of the mold 10 in order that the entire bell end of the mold may be kept sufficiently cool by the water circulating around the mold in the water box 11. The outer end of the driving sleeve 24 is so formed on its interior as to provide a shoulder 28 which is spaced longitudinally from the inner face 29 of an annular flange 30 around the bell end of the mold. The flange 30 is characteristic of many of the molds which are in use and constitutes a convenient means by which the driving sleeve 24 may be connected to the mold in the structures heretofore employed. As shown in the drawing, the face 29 of the flange 30 is somewhat curved, but it will be understood that this particular conformation is not essential to the present improvement.

Interposed between the inner face of the flange 30 and the shoulder 28 is a ring 31, preferably made of iron or steel. The ring 31 is tightly clamped between the shoulder 28 and the flange 30 when the parts are completely assembled, to thus form a rigid driving connection between the sleeve 24 and the mold, and a water seal between these parts. The outer surface of ring 31 is constructed to fit loosely within the outer end of driving sleeve 24 while its inner surface is substantially spaced from the outer surface of the mold so as not to interfere with the circulation of water around the entire bell end of the mold.

A flange ring 32 has the inner portion 33 of its inner face constructed to engage with the outer end of the bell of mold, particularly with the outer face 34 of the flange 30. The outer portion 35 of the inner face of the flange ring 32 is spaced substantially from the outer end of the driving sleeve 24, and the flange ring is secured to the driving sleeve by a plurality of bolts 36. These bolts extend through bolt holes 37 arranged around the periphery of the flange ring 32 and their inner ends are threaded into suitable openings 38 in the outer end of driving sleeve 24. An annular rib 39 on the inner face of the flange ring 32 extends between the mold flange 30 and the outer end of driving sleeve 24 for centering the mold with respect to the sleeve. A projecting flange 40 on the front face of flange ring 32 is provided with a plurality of tapered openings 41 to receive suitable wedges for retaining a bell core in position in the mold 10 in a manner well understood.

In view of the fact that mold flanges 30 vary somewhat in thickness, the improved driving and sealing ring 31 may have its inner and outer circumferential faces of different width, as by a tapered or offset end face, so as to be readily adapted to flanges of different thickness. As may readily be seen from the showing in Figs. 2 and 3, when the ring 31 is in the position shown in Fig. 2, with the shoulder 28 in engagement with offset portion 42, it may be used with a mold flange 30 of one thickness, and when the position of the ring 31 is reversed as shown in Fig. 3, with the projecting portion 43 in engagement with flange face 29, it may be used with a thinner flange 30 without any change in the driving sleeve 24 or the flange ring 32. Preferably the ring 31 is slightly rounded on the two edges which are adapted to contact with flange face 29, although this is not essential.

It will also be apparent from the drawing that the improvement is readily adapted to molds of

different diameter by utilizing the same driving sleeve 24 and merely substituting a driving and sealing ring 31 having a different thickness, and another flange ring 32 conforming to the change in diameter of the mold. As will also be apparent from the drawing, the structure of the improvement is such that the entire outer end of the bell of the mold, inwardly of the flange 30, is exposed to the circulating water in the water box 11 so that the temperature of the bell end of the mold may not become excessive during the casting operation.

It is desired to emphasize that with the use of the improvement no packing rings or sealing gaskets are necessary to provide a water seal between the driving sleeve 24 and the outer portion of the bell end of the mold. It has been found from extensive experiments with the device that the metal driving ring 31 seals the space between the driving sleeve 24 and the mold against water leakage when the bolts 36 are tightened to the extent necessary to clamp the flange 30 and the driving ring 31 between the flange ring 32 and the internal shoulder 28 on the driving sleeve. The improvement therefore not only eliminates water leakage around the bell end of the mold, but it dispenses with the use of packing or gaskets of a type which deteriorates quickly when in use with casting apparatus, and it has been found to effect a substantial saving in the labor and material necessary to avoid water leakage and to replace damaged and leaky packing and gaskets, and to repair damaged threads where a threaded connection is utilized between the flange ring 32 and the extension 44 on the bell end of the mold.

While a preferred form of the improvement has been disclosed herein, together with a certain arrangement of the parts thereof, it is to be understood that the invention is not intended to be limited to the precise apparatus and arrangement of parts disclosed. The above description and the accompanying drawing are therefore to be regarded as illustrative only, and it is to be understood that the invention is susceptible of other forms and arrangements so long as they come within the scope of the appended claims.

What I desire to claim is:

1. In centrifugal casting apparatus having a cylindrical mold rotatably and removably mounted in a water box and a driving sleeve surrounding one end of the mold and spaced therefrom, means for providing a driving connection and a water seal between said sleeve and said mold comprising spaced shoulders arranged circumferentially of said end of the mold to provide opposed radial clamping faces, an internal shoulder on said sleeve to provide a radial clamping face opposed to and spaced longitudinally from the innermost shoulder on said mold, a removable driving and sealing ring interposed between the shoulder on said sleeve and the innermost shoulder on said mold, a flange ring having its inner edge in engagement with the outermost shoulder on said mold and its outer edge spaced from the outer end of said driving sleeve, and means cooperating with said sleeve and said flange ring to clamp said driving and sealing ring in place.

2. In centrifugal casting apparatus having a cylindrical mold rotatably and removably mounted in a water box and a driving sleeve surrounding one end of the mold and spaced therefrom, means for providing a driving connection and a water seal between said sleeve and said

mold comprising spaced shoulders arranged circumferentially of said end of the mold to provide opposed radial clamping faces, an internal shoulder on said sleeve to provide a radial clamping face opposed to and spaced longitudinally from the innermost shoulder on said mold, a removable driving and sealing ring interposed between the shoulder on said sleeve and the innermost shoulder on said mold and having its inner face spaced from said mold, a flange ring having its inner edge in engagement with the outermost shoulder on said mold and its outer edge spaced from the outer end of said driving sleeve, and means cooperating with said sleeve and said flange ring to clamp said driving and sealing ring in place.

3. In centrifugal casting apparatus having a cylindrical mold rotatably and removably mounted in a water box and a driving sleeve surrounding one end of the mold and spaced therefrom, means for providing a driving connection and a water seal between said sleeve and said mold comprising spaced shoulders arranged circumferentially of said end of the mold to provide opposed radial clamping faces, an internal shoulder on said sleeve to provide a radial clamping face opposed to and spaced longitudinally from the innermost shoulder on said mold, a removable driving and sealing ring interposed between the shoulder on said sleeve and the innermost shoulder on said mold, a flange ring having its inner edge in engagement with the outermost shoulder on said mold and its outer edge spaced from the outer end of said driving sleeve, a rib on the inner face of said flange ring and extending between said mold and said sleeve to center the mold in the sleeve, and means cooperating with said sleeve and said flange ring to clamp said driving and sealing ring in place.

4. In centrifugal casting apparatus wherein a cylindrical mold having a circumferential flange at one end thereof is rotatably and removably mounted in a water box and a driving sleeve surrounds said end in spaced relation thereto, means for providing a driving connection and a water seal between said sleeve and said mold comprising an internal shoulder on said sleeve, a removable driving and sealing ring interposed between said shoulder and the inner face of said flange, a flange ring having its inner edge in engagement with the outer face of said flange and its outer edge spaced from the outer end of said driving sleeve, and means cooperating with said sleeve and said flange ring to clamp said driving and sealing ring in place.

5. In centrifugal casting apparatus wherein a cylindrical mold having a circumferential flange at one end thereof is rotatably and removably mounted in a water box and a driving sleeve surrounds said end in spaced relation thereto, means for providing a driving connection and a water seal between said sleeve and said mold comprising an internal shoulder formed on said sleeve and spaced longitudinally from the inner face of said flange, a removable driving and sealing ring interposed between said shoulder and the inner face of said flange and having its inner face spaced from said mold, a flange ring having its inner edge in engagement with the outer face of said flange and its outer edge spaced from the outer end of said driving sleeve, means on said flange ring for centering said mold with respect to said sleeve, and means cooperating with said sleeve and said flange ring to clamp said driving and sealing ring in place.

6. In centrifugal casting apparatus wherein a

cylindrical mold having an external shoulder thereon is rotatably and removably mounted in a water box and a driving sleeve with an internal shoulder thereon surrounds said mold, means for providing a driving connection and a water seal between said sleeve and said mold, comprising a removable driving and sealing ring interposed between said shoulders and having its inner face spaced from said mold, a flange ring having its inner edge in engagement with the outer end of said mold and its outer edge spaced from the outer end of said driving sleeve, a centering rib on the inner face of said flange ring and fitting loosely between said driving sleeve and said mold, and means cooperating with said driving sleeve and said flange ring to clamp said driving and sealing ring in place.

7. In centrifugal casting apparatus wherein a cylindrical mold having a circumferential flange at one end thereof is rotatably and removably

10 mounted in a water box and an internally shouldered driving sleeve surrounds said end in spaced relation thereto, a driving and sealing ring adapted to be clamped between the shoulder on said sleeve and said flange and having a radial face provided with opposite edge portions offset from each other whereby said ring may be reversed in position in said apparatus to adapt it to mold flanges of different thickness.

15 8. A driving and sealing ring adapted to be clamped between an internal shoulder on a driving sleeve and an external flange on a cylindrical mold in centrifugal casting apparatus, said ring having a cross section substantially rectangular with an annular portion of one radial face offset from the other portion whereby said ring may be reversed to adapt it to mold flanges of different thickness.

ROBERT E. DANIEL.
